END-SHOE FOR CURTAIN-HOLDERS
AND THE LIKE

Maria Faerber, New York, N. Y.

Application December 21, 1933, Serial No. 703,395

3 Claims. (Cl. 223—38)

In housecleaning and room-decorating work, it is generally found to be rather cumbersome work, to fix the hemstitch of laundered or new window-curtains or the like on the curtain-holders, because the sharp end-edges of the thin tubular rectangular or otherwise profiled rods of the curtain-holders are liable to catch with the meshes of the lace or other material, from which the curtains or draperies are made. Such damage to the curtain is in particular liable to happen, when handling the parts in the usual manner, according to which the curtain, from lying on the ground or on a table, must go up to the curtain-holder, which is held in a horizontal position higher up, and when accordingly thereto the curtain must go round the sharp end-corner of the holder, in order to be filed on the holder.

In order to overcome this inconvenience, I devised, a new and improved end-shoe for the curtain-holder. The object of this new and improved article is to facilitate the work of slipping the hemstitch of the curtain over the sharp end-edges of the curtain-holder. Another object of this article is, to prevent the fabric of the lace or the like from being torn, when it is drawn over the otherwise sharp corners of the curtain-holder. Another object of the invention is to provide an exchangeable end-shoe for curtain-holders, which may be fixed to or removed from the curtain-holder at will, so that one single end-shoe may be used for handling quite a number of curtains to be slipped over their respective curtain-holders, whereafter the end-shoe may be taken off and stored away. In certain cases, however, the end-shoes according to the invention, may be given a somewhat more refined artistic appearance, so that it can be left permanently on the end of the curtain-holder to form a decorative ending for the latter.

In the drawing, I have shown some embodiments of my invention, whereby Fig. 1 is an end-shoe to be slipped over a curtain-holder of rectangular cross-section;

Fig. 2 is an end-shoe to be slipped over a tubular curtain-holder of ring-shaped cross-section;

Figs. 3 and 4 are the connecting ends of shoes to be inserted into rectangular and tubular curtain-holders respectively;

Figs. 5 to 8 are different views of a curtain-holder and an end-shoe, which are modifications of the embodiment shown in Fig. 1.

Figs. 9 and 10 are endshoes of the type of

those shown in the Figs. 1 and 2 respectively, but provided at their open sleeve-ends with a longitudinal slot, such as that provided on the endshoes according to the Figures 5 to 8.

Referring now in particular to the drawing, in the first shown embodiment 11 is the end of a curtain-holder of rectangular cross-section. The end-shoe has a likewise rectangular open end 12, in its size slightly larger, than the curtain-holder 11, so that it may be slipped over 10 the end of the curtain-holder 11 and catches moderately firm on it. From this broader end 12 the shoe tapers as at 13, and preferably it ends in a rounded knob or head 14. The shoe of this construction, when fixed to the curtain-holder, will easily enter into the hemstitch of a curtain, even if the latter consists of fine laces. The operation of filing the end-shoe and subsequently the whole ledge 11 of the curtain holder into a hemstitch of a curtain is still more 20 facilitated, by having the tapered neck-part 13 of the shoe slightly curved downwardly, as indicated in Fig. 1, because such construction meets best the natural movement of the lace, which lying on the table or floor is drawn first vertically 25 up and makes then a turn or bow, on its way over the end-shoe, until it comes to rest on the horizontal curtain-holder.

The embodiment shown in the Fig. 2 is essentially of the same construction as that of 30 the first example, the difference being only, that on the end of a curtain-holder 16 of circular cross-section is slipped over the tubular open end 17 of the end-shoe, which is followed by the tapered and downwardly bent neck, 18, and 35 the ball-shaped head 19.

Whereas in the before described constructions the curtain-holder may be a solid piece of metal or wood, the modifications shown in the Figs. 3 and 4 are particularly adapted for hollow curtain-holders of rectangular or tubular cross-section 20, 21, which are preferably made out of sheet-metal. In adaptation to this the broader end of the shoe 22, 23, is preferably made solid, and its last end is set off, so as to form a rectangular pivot or dowel 24, respectively, a circular pin or dowel 25, the off-set shoulder between the parts 22, 24 or 23, 25, limiting the amount to which this end-shoe can be inserted 40 into the curtain-holder.

The embodiment according to the Figs. 5 to 8 is similar to that of the first example, in so far, as over a curtain-holder 26 of rectangular cross-section will be slipped an end-shoe, the open end 55

of which 27 is formed like a rectangular clamp 27 with slightly rounded shorter sides, and with a longitudinal slot 29 on its one longer side, providing thus greater elasticity to match the 5 end of the curtain-holder. The other end of the shoe changes in its shape into a more rounded form. This knob end 28 however is completely closed, so as to offer no sharp edges or points to the hemstitch to be slipped on it, and furthermore it is slightly bent down, so as to correspond better to the not yet filed vertically 10 depending part of the hemstitch to be slipped on it.

The Figures 9 and 10 in the drawing finally 15 show the two endshoes 30, 31, which correspond to those, shown in the Figures 1 and 2 respectively, except for the additional feature, that the open sleeve-like ends of them are provided with longitudinal slots 32, such as provided in 20 the embodiment according to Figures 5 to 8, and for the same purpose of giving to the sleeve-parts greater elasticity and resiliency for slipping the endshoe on the curtain-holder.

It is understood, that the invention is not restricted to the embodiments described before and illustrated in the drawing. As to the material from which the end-shoe according to the 25 invention may be made, I reserve the right to choose, whichever material fits best each particular case of the application: In one case, perhaps sheet-metal being the best, in other cases celluloid, in others again a solid construction of wood or of bakelite. If the end-shoe is made removable, to be united only temporarily to the 30 curtain-holder, then one single end-shoe can be used, as the tool to fix a number of different curtains to their respective curtain-holders. On the other side, if the end-shoe is left permanently on the curtain-holder as a decorative element, then it may be painted in colors to increase the 35 decorative effect.

I claim:

1. Device for slipping hemstitched curtains, draperies or the like over their holders, comprising: a body-part, the one end of which forms a lengthwise sleeve, adapted to be slipped over and to be fixed to the curtain-holder; a closed and rounded smaller knob or head-part opposite to the open end of the body-part; and a tapered horn-shaped and downwardly bent neck-part, connecting the body-part with the head or end-part and changing as to its cross-section and contours smoothly from the size of the body-part to the size of the knob or head-part, so as to facilitate the slipping of the device into the hemstitch of the curtain or the like. 15

2. Device for slipping hemstitched curtains, draperies or the like over their holders, comprising: a body-part, the one end of which is shaped to form a longitudinal continuation of the holder and adapted to be fixed on this 20 holder; an approximately ball-shaped head-part, the centre of which is situated at the side of the axis of the body-part; and a neck-part connecting the body-part and the head-part and changing in its contours smoothly from the 25 shape of the body-part to the shape of the head-part.

3. Device for slipping hemstitched curtains, draperies or the like over their holders, comprising: a body-part having a sleeve-like one end 30 adapted to the shape of the holder and to be slipped over the holder-end, this end-sleeve of the body-part having one wedge-like narrowing longitudinal slot; an approximately ball-shaped head-part, the centre of which is situated at the 35 side of the axis of the body-part; and a neck-part connecting the body-part with the head-part and changing in its contours smoothly from the shape of the body-part to the shape of the head-part.

MARIA FAERBER.
